UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT.

COLLAPSING TAP.

Application filed February 9, 1924. Serial No. 691,584.

To all whom it may concern:

Be it known that I, ALBERT F. BREITENSTEIN, a citizen of the United States, residing at New Haven, in the county of New Haven and State of Connecticut, have invented a new and useful Improvement in Collapsing Taps; and I do hereby declare the following, when taken in connection with the accompanying drawings and the characters of reference marked thereon, to be a full, clear, and exact description of the same, and which said drawings constitute part of this application, and represent in—

Fig. 1 a view in side elevation of one form which a tap constructed in accordance with my invention may assume, shown as collapsed.

Fig. 2 a view thereof in central longitudinal section, shown as set.

Fig. 3 a transverse sectional view of the tap on the line 3—3 of Fig. 2.

Fig. 4 a detached perspective view of the detent-carrying ring.

Fig. 5 a similar view of the detent.

Fig. 6 a view corresponding to Fig. 3, but showing a modified form of detent.

My invention relates to an improved collapsing tap, the object being to provide, at a low cost for manufacture, a compact, convenient and reliable tap, constructed with particular reference to ruggedness of construction and durability in use.

With these ends in view, my invention consists in a collapsing tap having a segmental detent arranged at a right angle to the longitudinal axis of the tap and released by the linear movement of a member of the tap, prior to collapsing the same.

My invention further consists in a collapsing tap having certain details of construction as will be hereinafter described and pointed out in the claims.

In carrying out my invention, as herein shown, I employ a tap-body 10 having an integral shank 11, by means of which the tap is mounted for use. The said tap-body mounts a detent-carrying ring 12 which has linear sliding movement upon it and which, in turn, mounts an operating-sleeve 13, which has linear sliding movement upon it.

At its rear end the tap-body is formed with a threaded shoulder 14 for the reception of an internally-threaded detent-abutment ring 15 having an integral, forwardly-projecting, annular flange 16 entering an annular space

17 formed within the rear end of the sleeve 13, and terminating at its forward end in an annular cam 18. The forward edge of the said flange 16 co-acts with the outer edge of the rear face of a segmental detent 19 arranged at a right angle to the longitudinal axis of the tap and thereto located within a transverse slot 20 formed toward the inner end of the detent-carrying ring 12, when the said detent has been moved radially outward in the slot by springs 21 acting upon plungers 22 engaging, as clearly shown in Fig. 3, with the bottom of the said slot, the said springs and plungers being located in holes 23 in the ends of the detent. The forward edge of the detent is formed with a bevel 24 for co-action with the annular cam 18 at the bottom of the space 17 in the operating-sleeve 13, so that, when the sleeve is moved rearward, its cam 18 co-acts with the level 24 of the detent to crowd the same inward against the tension of the springs 21, so as to disengage the outer edge of its rear face from the edge of the flange 16 of the detent-abutment ring 15.

The detent-carrying ring 12 is coupled to the plunger 25 by means of a transversely-arranged coupling-bar 26 passing through a diametric slot 27 in the plunger and through a diametric clearance-slot 28 in the tap-body, its ends being entered into slots 29 in the ring itself, as shown in Fig. 3, whereby the said ring moves the said plunger when the tap is set, and the plunger moves the ring when the tap is tripped, the clearance-slot 28 in the tap-body being long enough to permit the ring and plunger to have sufficient conjoint movement to permit the collapsing and resetting of the tap.

At its rear end the plunger has screwed into it the inner end of a plunger-screw 30, mainly located in a bore 31 in the shank 11 of the body. The said screw carries a helical tap-collapsing spring 32 interposed between its head 33 and a washer 34 abutted against a shoulder 35 produced at the inner end of the bore 31 by making the same larger than the bore 36 formed in the tap-body for the reception of the plunger 25.

At its forward end the tap-body is formed with equidistant radial slots 37, respectively receiving chasers 38 held in place by a cap 39 fastened to the front face of the body. These chasers are formed in the usual manner with inclined slots 40 receiving under-

cut inclined ribs 41 formed integral with the forward end of the plunger 25.

At its forward end, the detent-carrying ring 12 is formed with an annular flange 42, which co-acts with the forward end of the operating-sleeve 13, as will hereinafter appear.

The operation of my improved tap is as follows:

- 10 As shown in Fig. 2, the chasers of the tap are in their projected or cutting positions, in which they are firmly held against the tension of the collapsing-spring 32 by the engagement of the outer edge of the inner face of the detent 19 with the edge of the annular flange 16 of the detent-abutment ring 15, the detent being at this time held in its operating position by its springs 21, its outer face being, at this time, projected beyond the periphery of the detent-carrying ring 12. Now, assuming that the cutters 38 have performed their work and it is desired to withdraw them therefrom, the annular flange 43 of the operating-sleeve is engaged 25 by a suitable abutment (not shown) of the machine in which the tap is being used, whereby the sleeve is moved rearward with reference to the tap toward the position in which it is shown by broken lines in Fig. 2.
- 30 This rearward movement of the sleeve away from the flange 42 of the ring causes the cam 18 of the sleeve to act upon the bevel 24 of the segmental detent 19, which is thus crowded radially inward into its slot 20 against the tension of the springs 21, until it is brought down flush with the periphery of the ring 12, at which time it is disengaged from the flange 16 of the detent-abutment ring 15, whereby the spring 32 is permitted 35 to pull the plunger 25 rearward and thus positively retract the chasers 38 into their collapsed or clearance positions, as shown in Fig. 1, in which they clear the work.

Through the medium of the coupling-bar 45 26, the detent-carrying ring 12 is retracted with the plunger 25, whereby the detent 19 is carried within the forwardly-projecting flange 16 of the ring 15, where it remains until the tap is reset by pushing forward on the flange 43 of the operating-sleeve 13, the forward edge of which engages with the flange 42 of the ring 12, which then moves forward with respect to the tap-body 10. As the ring 12 moves forward, it correspondingly moves the plunger 25 through the medium of the coupling-bar 26, whereby the spring 32 is compressed and the chasers projected. At the limit of this forward movement just described, the segmental 50 55 60 detent 19 escapes, as it were, from its confinement within the annular flange 16 of the ring 15 and snaps into engagement with the edge thereof, as shown in Fig. 2. The

detent now acts to hold the chasers in their projected or cutting positions until the tap is again tripped by the co-action of the flange 43 of the sleeve 13 with a suitably-placed abutment of the machine. It may be stated here that the means for operating the sleeve 13 for collapsing and resetting the tap has nothing to do with my present invention. I have shown a rotary tap, but the invention is equally applicable to a tap adapted to have its operating-sleeve engaged for manual operation.

In the modified construction shown by Fig. 6, the segmental detent 44, instead of moving bodily outward in a transverse slot in the detent-carrying ring, has one end pivoted therein upon a pivot 45, while its opposite end is provided with a spring-plunger 46. This pivotal segmental detent 44 operates, to all intents and purposes, in the same manner as the radially-movable, segmental detent 19 already described, the segmental detent in either case moving in a plane transverse to the axis of the tap.

I claim:

1. In a collapsing tap, the combination with the body, chasers, plunger and collapsing-spring thereof; of a ring having sliding movement upon the said body and formed with a transverse slot, a segmental detent located in the said transverse slot and having movement therein in a plane transverse to the axis of the tap, an operating-sleeve having sliding movement upon the said ring and co-acting with the said detent to force the same into its retired position in the said slot, and a detent-abutment ring having an annular flange entering the said sleeve into position to co-act with the said detent when in its operating position for holding the cutters in their projected positions and against the power of the said spring.

2. In a collapsing tap, the combination with the body, chasers, plunger and collapsing-spring thereof; of a ring having sliding movement upon the said body and formed with a transverse slot, a segmental detent located in the said slot, a spring for operating the said detent, an operating-sleeve having sliding movement upon the said ring and co-acting with the forward edge of the said detent for retiring the same against the action of its spring, and a detent-abutment ring mounted upon the tap-body, entering the rear end of the said sleeve and engaging with the outer edge of the rear face of the detent to hold the plunger in its forward position against the power of the collapsing spring.

In testimony whereof, I have signed this specification.

ALBERT F. BREITENSTEIN.
